Attorney

UNITED STATES PATENT OFFICE.

WALTER S. WOODWARD, OF GREAT FALLS, MONTANA.

SIGNALING DEVICE.

1,368,677.

Specification of Letters Patent. Patented Feb. 15, 1921.

Application filed October 11, 1919. Serial No. 330,080.

To all whom it may concern:

Be it known that I, WALTER S. WOODWARD, a citizen of the United States of America, and resident of Great Falls, in the county of 5 Cascade and State of Montana, have invented certain new and useful Improvements in Signaling Devices, of which the following is a specification.

This invention relates to signaling devices, and particularly to an apparatus for use in timing the duration of treatment of articles in vulcanizing machines or the duration of a baking process; in fact, the said invention may be used in different industries 15 for the purpose of signaling an operator when the time has arrived to perform a duty.

I will describe the invention in its use in connection with vulcanizing machines, and from it an understanding of its advantages 20 will be gained for its use in other arts.

As is well known, the treatment or baking of rubber tubes while being patched, or the repairing of casings during the vulcanizing, must be timed so as to prevent overcooking, 25 and where a number of vulcanizing machines are used it has been found difficult to keep track of the times when the articles being treated should be removed.

It is an object of this invention, therefore, 30 to produce novel means whereby an alarm will be given after a certain time has elapsed, and when said signal is given an operator may observe, by numbers or other designating characters, which of the machines 35 have been operating for the period of time indicated by the signal, and a plurality of machines may be indicated each five minutes or each two and a half minutes by a timing device such as a clock.

40 A still further object of this invention is to provide novel means whereby a minute hand of the timing device will be caused to establish a circuit for supplying electricity to a signal, such as a bell, whereby the said signal will remain in action for a given period of time or until the circuit is manually interrupted.

45 A still further object of this invention is to provide a novel manually operative contact with which the minute hand coacts, it being understood that the manually operated members may be multiplied so as to establish a circuit through the minute hand each two and a half or five minutes, according to 55 the requirements in practice.

With the foregoing and other objects in

view, the invention consists in the details of construction and the arrangement and combination of parts to be hereinafter more fully set forth and claimed.

60 In describing the invention in detail, reference will be had to the accompanying drawings, forming part of the specification, in which the preferred embodiment of the invention is illustrated, and in which—

65 Figure 1 illustrates a plan view partly in section of a timing mechanism embodying the invention;

70 Fig. 2 illustrates a diagrammatic view of the circuit for the signal, and

75 Fig. 3 illustrates enlarged detail view of the manually operated contact and an extension of the minute hand adapted to coact therewith.

80 In these drawings 5 denotes a casing, having a metal cover 6, with a glazed central opening 7, through which the dial 8 of a timing device may be observed. The said timing mechanism has the usual hour hand 9 and the usual minute hand 10, the latter carrying an extension 11, which is preferably resilient.

85 A series of contacts 13 are arranged around the dial in such position as to be engaged by the extension of the minute hand, if the contact is set for engagement with the minute hand, but unless so set the minute hand may be freely moved with relation to the contact without establishing a circuit in passing it.

90 Each contact comprises in its construction a push button 14 on the outer end of a shank 15, and each shank is slidably in an aperture 16 in the cover 6. A spring 17 is interposed between the push button and the cover, the said spring surrounding the shank and serving to urge the said shank normally upwardly. Near the inner end of each shank there is a shoulder 18, having a notch or seat 19 which is engaged by an 100 arm 20 of the yoke 21, the said yoke being attached to the under side of the cover and the said arm depending therefrom. The shank 15 carries a terminal or contact 22, which is engaged by the extension 11 of the 105 minute hand when the device is set, as shown in Fig. 3, to coact with the said minute hand; but if the push button is depressed to unseat the shoulder from the arm and the said shank is slightly oscillated to 110 carry the shoulder out of alignment with the arm, and the push button is then released,

the spring will serve to push the shank outwardly so that the terminal or contact 22 will be out of the path of travel of the extension of the minute hand and the said minute hand may then move past the contact without engaging it.

An apertured disk 23 is rotatable around each shank 15 and the said disk is supported on the cover 6. The disks are preferably 10 provided with marginal numerals as here shown running from 1 to 8 and the cover is supplied with an indicating point 25 for each disk with relation to which the disk is rotatable so that the number which is opposite the indicator will denote the machine which has been charged and the alarm for which has been sounded when the minute hand engages the contact carried by the shank at that point. By this arrangement, 20 it is possible to sound an alarm for any one of the machines each five minutes and in vulcanizing machines an operator could be informed by reference to this indicator when any one of the vulcanizing bakers has 25 been in operation the limit of time set by an operator.

I claim:

1. In a signaling device, a timing mechanism having a dial and a minute hand, an

extension on the minute hand, a cover for 30 the timing mechanism under which the minute hand moves, the said cover being electrically connected to the timing mechanism, contacts extending through the cover and adapted to contact by the extension of 35 the minute hand, a numbered movable portion associated with each contact, and means for establishing a circuit to a signal when the extension of the minute hand engages a contact.

2. In a signaling device, a timing mechanism having a minute hand, a resilient extension on the minute hand, contacts each comprising a slidable shank and a push button, with means for urging the shank outwardly, and a recessed shoulder on the shank engaged by an arm to hold the shank in set position, a casing for the timing mechanism electrically connected to the timing mechanism and having means for supporting the contacts, a member carried by the shank for engaging the extension of the minute hand, a signal and electric circuit, including a source of electricity, the said contact constituting one terminal of the 55 said circuit and the minute hand constituting the other terminal of the said circuit.

WALTER S. WOODWARD.
